UNITED STATES PATENT OFFICE

CURT HILSCHER, OF CHEMNITZ, GERMANY

PROCESS OF PRODUCING STOCKINGS ON FLAT-KNITTING FRAMES

Application filed May 7, 1928, Serial No. 275,916, and in Germany June 5, 1925.

This invention relates to a process of producing socks and stockings in one operation so that to the lower portion of the heel of the stocking a pouch-like widening is given. 5 Care has to be taken that the well known inner transferring line which limits the heel is preserved in its usual shape. Without preserving this line a widening by means of two needles would be sufficient to obtain the heel- 10 widening over the entire lower portion of the heel. The widening in preserving the inner transferring line of the heel is obtained, according to the invention, by transferring every two rows of loops from the beginning 15 of the heel on both sides of the fabric in outward direction, first by one needle, whereupon the travel of the thread-guide is lengthened in outward direction by two needles. As soon as the border-loop has been completed, for 20 which two rows are required, the heel has been widened during the knitting of these two rows by two needles, one needle-widening by the transferring and a second needle-widening for which the thread-guide has travelled 25 beyond the widening needle. On the inner boundary line of the heel only the transferring is effective and not the widened travel of the thread-guide. The lower portion of the heel is knitted in this manner whereupon the 30 widening of the travel of the thread-guide is stopped and the transfer points continue to transfer, in a manner known per se, a narrower piece up to the upper end of the heel.

The process is illustrated, by way of example, on the accompanying drawing which shows in the only figure a stocking as it comes from the knitting frame.

As soon as the knitting from the heel-portions II and III continuing the leg I and the 40 middle portion IV begins, the heel is transferred in outward direction at either side of the fabric by one needle with the transfer points, extending from the inner boundary line of the heel to the maximum heel-width. 45 The thread-guide which follows then moves in outward direction a distance of two needles more than in the preceding row y, whereupon a second row is knitted, in order to finish the loops, specially on the edge. The transfer 50 points begin then to work again and shift the

last row of heel-loops by one needle in outward direction, and the thread-guide extends its travel by two needles, whereupon, after the knitting of the second row, the widening by one needle, followed by a widening by a second needle through the lengthened travel of the thread-guide by two needles and so forth takes place, until to the heel a special widening has been given in its lower portion from e to a and from f to b (Fig. 1).

From now on the travel of the thread-guide is not lengthened any more, the width of travel remaining the same to the end c and d of the heel. A number of the transfer points are now rendered inoperable while the remaining transfer points work from the loop-row a to b on only the narrower row x of the heels after each row by one needle in outward direction up to the ends c and d of the heel-portions.

A pouch-like widening is given to the heel-portions II and III by this proceeding, said widenings being indicated on the drawing by the triangles e, a, g and f, b, h, the inner boundary line of the heel being preserved in a manner known per se.

I claim:—

A process of producing stockings with widened heel-portions on the flat knitting frame in which widening takes place up to the obtention of the maximum heel-width, consisting in making from the beginning of the heel-portions first transfer by the transfer points the heel-loops by one needle at either side of the fabric in outward direction, 80 in then lengthening the travel of the thread-guide by two needles, in transferring in outward direction again by one needle after two rows of loops have been knitted, in lengthening the travel of the thread-guide by two 85 needles until a pouch-like widening of the heel has been obtained, in continuing then the travel of the thread-guide in the same width, and in making the transfer points continue to work only in the width up to the end 90 of the heel.

In testimony whereof I affix my signature.
CURT HILSCHER.
